UNITED STATES PATENT OFFICE.

THOMAS CLORE, OF WAVELAND, INDIANA.

ROAD-GATE.

SPECIFICATION forming part of Letters Patent No. 248,405, dated October 18, 1881.

Application filed July 27, 1881. (No model.)

To all whom it may concern:

Be it known that I, THOMAS CLORE, a citizen of the United States, residing at Waveland, in the county of Montgomery and State 5 of Indiana, have invented new and useful Improvements in Road-Gates, of which the following is a specification.

This invention relates to that class of gates adapted to be operated by equestrians or persons in vehicles; and it consists in the combination, with a gate and its latch, of a top hinge composed of a horizontally-oscillating lever having a pivotal connection with the top of the gate-post and the top of the adjacent fence-post, the lower hinge being of ordinary construction, so that if this hinge-lever is swung in either direction the gate is thereby brought to a diagonally-inclined position, the effect of which is to lift the latch and cause the gate to 15 swing open automatically. The hinge-lever is operated by means of a reciprocating rod, which projects in opposite directions therefrom along the road, and to the respective ends of which is connected a handle pivoted to the 20 top of a suitable post for giving motion to the 25 rod.

This invention is illustrated in the accompanying drawings, in which—

Figure 1 is a perspective view, showing the 30 gate closed. Fig. 2 is a plan or top view of the gate-operating mechanism, showing the position thereof when the gate is closed. Fig. 3 is a similar view thereof when the gate is set to open. Fig. 4 is a side view of the gate 35 closed. Fig. 5 is a similar view thereof when it is set to open.

Similar letters indicate corresponding parts.

The letter A designates the gate. B is the latch; C, the lever composing the top hinge; 40 D, the reciprocating rod, and E the handles.

The gate A is constructed with end posts, F' F², and it is arranged between fence-posts G' G², both the gate-post F² and the fence-post G² being preferably inclined inwardly. (See 45 Fig. 4.)

The latch B is of ordinary construction, and catches in a recess, H, formed in the post G² in a known manner.

The hinge-lever C is used in conjunction with

a lower hinge, I, of ordinary construction, and 50 it is pivoted to the top of both the gate-post F' and the fence-post G', to oscillate in a horizontal plane. Said lever C, moreover, is pivoted to the rod D at or near its mid-length, so that the rod projects in opposite directions 55 from the lever, its direction being transversely to the gate and parallel to the road in which the gate is used, and the handles E are connected to the ends of the rod, respectively, these handles being pivoted to the top of 60 posts J.

When the gate A is closed the hinge-lever C and handles E are substantially parallel to each other and parallel to the gate, while if one of the handles is swung in either direction the hinge-lever shares its motion through the rod D, and the lever acts on the gate to draw the top thereof both toward the top of the fence-post G' and sidewise, as indicated in Figs. 3 and 5, so that it assumes a diagonally- 65 inclined position, and it will be seen that the latch B is thus lifted to free the gate, while the latter opens automatically or by its own weight in the direction of its lateral inclination. If either of the handles E is then re- 70 turned to a normal position, the gate closes. 75

By the rod D and handles E equestrians or others are enabled to open the gate on approaching the same, and to close it after passing through the gateway, without dismounting; but a similar result can also be obtained by substituting ropes for the rod and handles. 80

I am aware that it is not new to construct a gate with its upper hinge composed of a lever pivoted to the gate-post, or to an inclined bar 85 on the gate, and operated by a series of levers and connecting-rods. My device is simpler in construction, having but a single connecting-rod with the hinge-lever, and one handle at each end of the former.

I am also aware that a slotted plate has been employed on the hinge-lever, playing on pins in an opening in the fence-post, to allow of a tilting movement of the gate to release it from its latch. My invention is simpler in construction, in that no slotted plate is employed, and, furthermore, embraces a gate having its outer frame-post slanting and its outer gate-post also 90 95

slanting, so that the latch is readily released therefrom in the initial movement of opening the gate.

What I claim as new, and desire to secure 5 by Letters Patent, is—

The combination, with the swinging gate provided with a latch and connected with the fence-post by a lower hinge, I, of the lever C, pivoted at one end to the gate-post, at its opposite end pivoted to the long straight bar D, and at a point between its ends pivoted to the top of the fence-post, and the handles E, piv-

oted both to the posts J alongside of the road and to the ends of the bar D, said members being all constructed and organized as herein 15 shown and specified.

In testimony whereof I have hereunto set my hand and seal in the presence of two subscribing witnesses.

THOMAS CLORE. [L. S.]
